Primary Examiner—Doris V. Coles
Attorney, Agent, or Firm—Banner & Witcoff, Ltd.[57] **CLAIM**

The ornamental design for an element of a shoe upper, as shown and described.

DESCRIPTION

FIG. 1 is a side elevational view of an element of a shoe upper showing my new design;

FIG. 2 is a side elevational view of the other side thereof;
FIG. 3 is a front elevational view thereof;

FIG. 4 is a rear elevational view thereof; and,

FIG. 5 is a top plan view thereof.

The broken line showing of a shoe in FIGS. 1-5 is for illustrative purposes only and forms no part of the claimed design.
